UNITED STATES PATENT OFFICE.

ROBERT R. PARRY, OF NEW YORK, N. Y., ASSIGNOR TO AUTOMATIC HOTEL SERVICE CO., A CORPORATION OF MAINE.

DISH-RECEIVER.

No. 904,010.

Specification of Letters Patent.

Patented Nov. 17, 1908.

Application filed March 18, 1907. Serial No. 363,097.

To all whom it may concern:

Be it known that I, ROBERT R. PARRY, a citizen of the United States, and a resident of New York, Bronx borough, in the county 5 and State of New York, have invented certain new and useful Improvements in Dish- Receivers, which improvements are fully set forth in the following specification.

This invention relates to improvements in 10 dish receivers, the same being available for receiving dishes when cleansed by mechanical or other means.

The object of this invention is to provide a dish receiver which shall be simple and 15 comparatively inexpensive as regards construction; which shall embody novel selective features whereby the receiver is rendered capable of receiving and temporarily storing dishes of various sizes, contours and depths; 20 which shall be durable, efficient and reliable in practical service; and which shall possess certain well-defined advantages over prior analogous constructions.

The invention consists in the novel combinations, details and parts whereby, together with the novel relative disposition of said parts, the attainment of the foregoing object is rendered practicable, all of which will be more specifically referred to herein- 30 after and set forth in the appended claims.

The invention is clearly illustrated in the accompanying drawings, wherein like reference-numerals denote corresponding parts throughout the several views, as to which:

35 Figure 1 is a plan view of a dish receiver constructed in accordance with my invention. Fig. 2 is a side elevation thereof. Fig. 3 is an enlarged, detail sectional view, the section being taken along the line $x-x$ 40 of Fig. 1. Fig. 4 is an enlarged, detail sectional view, the section being taken along the line $y-y$ of Fig. 1, and Fig. 5 is an enlarged, detail sectional view, the section being taken along the line $z-z$ of Fig. 1.

45 In a general sense my present invention comprises a channel for the reception of dishes; means for feeding dishes, one after the other, into said channel; and means for feeding each dish as it assumes a position of 50 rest within said channel, against impact from the next following dish.

It further comprises, in a general sense, a plurality of channels, each for receiving dishes of a particular size, contour or depth; 55 means for feeding dishes for delivery into

said channels; and selective means for insuring the delivery to and into any one of said channels, of dishes of the particular size, contour or depth for the reception of which such channel is provided.

Having reference to the accompanying drawings, I provide, in carrying out my invention, feed mechanism for feeding dishes irrespective of the size, contour or depth thereof, for delivery into my improved dish receiver proper, such feed mechanism comprising, in this instance, opposing rollers 2, 3, on which operates an endless apron 4, said rollers being journaled, respectively, in a suitable frame-structure, here shown as 70 consisting of opposing side-pieces 5, 6, and an end-piece 7, connecting said side-pieces, and suitable means, as the legs 8, 9, 10, and 11, being provided for supporting said frame-structure.

Any approved means may be availed of for imparting movement to either of the rollers aforesaid, and hence to the apron 4. In this connection, however, I purpose to extend one of said rollers, as 2, outwardly 80 from the frame-structure in which it bears, and provide the same with a sheave or pulley 12, on which operates a belt 13, in communication with any appropriate source of power and motion.

For the reception from the apron 4, of circular and comparatively shallow dishes, as plates, saucers, and the like, I provide a primary receiving trough 14. This trough is arranged at an inclination downwardly from 90 the plane of the apron 4, extends only partially along the delivery point 15, thereof, and hence receives dishes only from a corresponding portion widthwise of said apron. The trough 14 is, by preference, provided 95 interiorly with a facing or cushion 16, of sheet rubber, or other suitable material, and is continued in its downward inclination to form a box-like head 17, which communicates with a temporary storage channel 18, 100 by way of a suitable opening 19, formed in the adjacent, laterally inclined wall of the head 17.

The laterally inclined wall aforesaid, of the head 17, is rounded or curved somewhat at the approach to the opening 19, as clearly indicated in the drawings.

The channel 18 is arranged at an inclination downwardly from the opening 19, and is formed by duly assembling appropriate 110

side-members, an end-member at the lower extremity thereof, and a suitable bottom portion, as also clearly indicated in the drawings.

5 The head 17 and channel 18 are, respectively, provided, by preference, with an interior facing or cushion, similar to 16, of sheet-rubber, or other suitable material. Hence, motion having been imparted to the apron 4, 10 a circular, shallow dish placed or delivered upon said apron will be delivered thereby edgewise to and into the primary receiving trough 14, whereupon said dish, always inclining against the inclined wall of said 15 trough adjacent to said apron, will voluntarily undergo a rolling movement downwardly along the trough 14, and still downwardly along the interior of the head 17, until it reaches the opening 19; whereupon, if 20 its diameter relative to the height of the opening 19 be suitable, it will voluntarily pass through said opening and into and downwardly along the channel 18. Naturally, another dish of suitable diameter, 25 delivered by the apron 4 into the trough 14, would correspondingly traverse the same course; but in the absence of means to avert such a contingency, the dish last to enter the channel 18 would engage the dish first entering 30 said channel with a more or less hazardous impact, which would, in most if not all, instances result in the breakage and hence destruction of one or both of said dishes.

To obviate the foregoing objectionable results, I arrange at intervals along the channel 18, a series of movable fenders 20, each capable of being automatically adjusted by a dish traversing, and ultimately assuming a 40 manner to fend such dish against impact from the next incoming dish.

The particular form of each of the fenders 20 may be widely varied as occasion may suggest or render advisable, the essential 45 function thereof being, each to fend one dish which shall have reached its destination along the channel 18 against impact from the next following dish.

More specifically with reference to the 50 fenders used in conjunction with the channel 18, each is here shown as being elongated and approximating the form of a lever, working on a pivot 21. This specific form of fender is desirable only where lateral pockets 22 are 55 provided, along and at one side of the channel 18; and such pockets are provided only to permit lateral deflection of the shallow dishes entering said channel and the presentation thereof facewise within the channel, 60 each with respect to its neighbor, thereby economizing space. The pockets 22 are arranged in a series, one somewhat in advance of the pivotal point of each of said fenders, and of the latter each normally lies parallel 65 with the channel 18, with its forward por-

tion closing the entrance to the pocket in conjunction with which it cooperates.

Where the pockets 22 are employed it is essential that means, as the deflector 23, be provided at the lower terminus of the channel 18 for deflecting the dish first entering the channel into the lowermost pocket 22; and as the adjacent fender 20 normally spans the entrance to said pocket, it is engaged by said dish and thereby automatically adjusted 70 so that its rear portion projects across the channel 18 proper, in such a manner as to fend the dish thus pocketed against impact from the next incoming dish, and incidentally divert the latter into the next uppermost 75 pocket, and so on, as the dishes are received, one after the other, into said channel.

Any desired number of the pocketed channels 18, each of proper dimensions widthwise, and provided with a series of fenders 80 20, may be availed of; and where a plurality of such channels are availed of, they may be conveniently arranged each parallel with, and alongside its neighbor, and within a general box-like structure 24, the latter being 85 supported in any approved manner, as by means of pairs of legs 26, 27.

Under the foregoing arrangement of a plurality of channels 18, the inclined wall of the head 17, adjacent to such channels, is 90 provided with an additional opening 25*, by way of which communication is established between the head 17 and the channel 18 next adjacent to that between which and said head communication is established by way of the 100 opening 19; but the opening 25* should be of greater height than the opening 19, to accommodate dishes of correspondingly greater diameter,—and so on with each succeeding opening made use of, of the character now 105 under discussion, there being provided as many of these openings as there are channels 18, and the same serving as selective means for assorting the dishes coming into the head 17, and directing them into their proper 110 channels according to the diametric size thereof.

In some instances an additional channel 18 may be provided to receive dishes direct from the head 17, provision being made to 115 this end, preferably by leaving the latter open at the end thereof most distant from the trough 14, as clearly indicated in the drawings.

Attention is here called to the fact that the 120 dishes delivered into the trough 14, by the apron 4, primarily assume therein, each the position indicated in Fig. 3 of the drawings; and hence the same may escape from said trough either by a rolling movement along 125 the bottom thereof, or by a sliding movement along the wall thereof against which such dish inclines.

For the reception and temporary storage 130 of dishes of that type commonly known as

platters, and the like, I provide an additional channel 29, which in all essential details is a counterpart of any one of the channels 18, the same being arranged at an inclination 5 downwardly from that side of the trough 14, opposite the apron 4, and being of suitable dimensions widthwise. I further provide within the channel 29 a series of fenders 30 which conform, each, in essential function 10 and mode of operation, to any one of the fenders 20, the same being pivotally disposed, and serving each to fend a dish received and at rest within said channel, against impact from the next incoming dish 15 delivered to said channel. More specifically, in this connection, each of the fenders 30 is fingered, substantially as shown in the drawings, or formed to normally intersect somewhat its neighbor, and operates on pivots at 20 the points 31, 32. Again, under normal conditions, the fenders 30 form approximately a false bottom for the channel 29; and as dishes are delivered, as through the medium of the apron 4, and one after the other, into 25 said channel, they voluntarily slide downward along said fenders thus normally arranged, the dish first to enter said channel, consequently, reaching and passing slightly beyond the axis of movement of the lowermost fender 30, whereupon it tilts downwardly, taking the lowermost portion of said fender with it, and hence accordingly adjusting said fender so that its upper portion projects more or less upwardly at the rear of 30 said dish, and thus serves to fend the latter against impact from the next incoming dish,—this operation being repeated with the next higher normally arranged fender, by the action of the next incoming dish, and 35 so on throughout the entire series of fenders 30.

To insure the retention of each of the dishes received in the channel 29, in its tilted position, as above alluded to, and as clearly 40 shown in Fig. 3 of the drawings, I arrange along the bottom of said channel, at suitable intervals apart, cleats 33, the same forming, as it were, pockets 34, which correspond in a measure with the pockets 22, (Fig. 1), and 45 into each of which projects the lower edge of a dish, when received within the channel 29 and tilted as stated.

Each of the cleats 33 is covered, by preference, with a strip of sheet-rubber 35, or other 50 suitable material.

The structure 37 forming the channel 29 may be attached to the trough 14 in any appropriate manner, as by providing the same, at its upper end, with a cross-piece 36, having a pin 38 projecting downwardly therefrom, and into a suitable opening formed in the adjacent side-portion of said trough, as clearly indicated in Fig. 3. This construction, as will be seen, permits ready detachment of said structure 37 from the trough 14.

In relatively adjusting the fenders 30, for the movement of dishes therealong, as hereinbefore referred to, this may be accomplished by hand or in any other suitable manner.

To the side of the trough 14, adjacent to the upper end of the structure 37, there is hinged a bridge 39, having a facing 40, of sheet-rubber or other suitable material, at its inner side, and a like facing 41 at its outer side, the facing 40 merging into a curtain 43, which serves, in addition to the facing or cushion 16, to prevent breakage of any dishes delivered into the trough 14, as when the bridge 39 occupies its upright position, 70 as shown in full lines in Fig. 3. Through the medium of the hinges 44, however, the bridge 39 may be turned downward, so as to span the trough 14, at an inclination from the apron 4 downwardly to the entrance of channel 29, as indicated in dotted lines in Fig. 3. When the bridge 39 occupies its last named position, the dishes delivered thereto by the apron 4, gravitate downwardly along the upper side of said bridge, accordingly enter the channel 29, and accordingly move downwardly along the normally arranged fenders 30, said dishes being delivered by the apron 4 to the bridge 39 one after the other. 80

Naturally, when the bridge 39 occupies its upright position dishes may be delivered directly into the trough 14, as hereinbefore described.

Attention is here called to the fact that 100 the bridge 39 serves, when spanning the trough 14, as selective means for insuring the delivery, in the operation of the apparatus as a whole, to and into the channel 29, of dishes of that particular type for the reception and temporary storage of which said channel is provided.

Again, for the reception and temporary storage of dishes of that type commonly known as cups, bowls, and the like, I provide still an additional channel 45, the same being arranged in this instance parallel with and alongside of the channel 29, and at an inclination downwardly from the delivery point of the apron 4, and that portion of said 110 apron which does not deliver into the trough 14, delivery from said apron being accordingly made directly into said channel 45. This last-named channel is of proper width to suit the purpose for which it is intended, and otherwise conforms in all essential details to the channel 29, or any one of the channels 18. I further arrange within, and at intervals along, the channel 45, a series 120 of fenders 46, which conform, each, in essential function and mode of operation, to any one of the fenders 20, or the fenders 30, the same being pivotally disposed, and serving each to fend a dish received and at rest within said channel, against impact from 130

the next incoming dish delivered to said channel. More specifically, in this connection, and for convenience in the disposition of said fenders 46, I make use of a universal-bar 47, whose lower end is reduced, as shown, to enter a suitable opening formed in the lower end-piece of the structure 48, whereby the channel 45 is formed, and the upper end of which bar engages a yoke 49, which spans the channel 45, at the upper end thereof. This yoke 49 merely rests upon the opposing side-members of the structure 48, the bar 47, with its yoke 49, being thus rendered easily removable from the structure 48, whenever occasion may make the same desirable.

The fenders 46 work, each, on a pivot 50, and are thus disposed at intervals along the bar 47, and hence the channel 45. They approximate, each, a bell-crank in form, one of whose arms normally depends by its own gravity into the path of the dishes coming into said channel. Accordingly, the dish first to enter and move downwardly along said channel, engages the normally depending arms of said fenders, one after the other, lifting each somewhat and releasing it for a return movement, as by its own gravity, until said dish shall have reached its position of rest within said channel, as at the lower end thereof; and in arriving at its said position of rest, said dish will have moved the lowermost fender 46 into substantially the position which the next higher fender 46 is shown as occupying in Fig. 3, and will continue to hold the same in this position, with its other arm projecting somewhat into the path of the incoming dishes. Hence, the last-named arm of said lowermost fender is engaged by the next incoming dish, and is thereby moved towards and against the dish aforesaid next in advance thereof, where it serves to fend the latter against dangerous impact from said next incoming dish; and so on, throughout the entire series of fenders 46, as the dishes are fed, one by one, into the channel 45.

The fenders 46 are each formed from wood, or other suitable material.

It is desirable that means be provided whereby dishes, intended for the channel 45, and delivered to that portion of the apron 4 which otherwise delivers to the trough 14, or bridge 39, may be deflected towards and for entrance into the channel 45; and in this connection I provide a bar 51, removably or shiftably secured at one of its ends, as at the point 52, to the side-piece 6, (Fig. 1), and projecting therefrom obliquely across and somewhat above the apron 4, its free end terminating at the entrance to the channel 45.

I also provide, by preference, a brace 53, which is temporarily secured tightly to the bar 51, in any approved manner, as by means of a thumb-nut 54, and whose free end abuts against the inner side of the side-piece 6,

when the parts occupy the position indicated in full lines in Fig. 1. Naturally the free end of the brace 53 may be loosely and even removably secured to said side-piece, in any common and well known manner.

In practice, the bar 51, with its brace 53, may be shifted, when not required for service, to one side of the apron 4, as indicated in dotted lines in Fig. 1, and hence out of the way of any dishes carried by and moving with the apron 4; or, shallow dishes, as plates, saucers, and the like, may pass under the same, even when adjusted for the deflection of deeper dishes, as cups, bowls, and the like, in the direction of the channel 45. In this connection attention is called to the fact that the deflector or bar 51 serves as selective means for insuring the delivery to and into the channel 45 of dishes of that particular type for the reception and storage of which said channel is provided. It is further pointed out that the fenders made use of in conjunction with the several storage channels of the apparatus, are automatically actuated, each by a dish received in the channel whereat such fender is located, and accordingly set or adjusted so as to fend such dish against dangerous impact from the next incoming dish.

The operation of my improved dish receiver will be apparent from the foregoing description thereof; and while the same is more particularly intended for service in conjunction with a mechanical construction for washing dishes, and which shall be capable of delivering to the apron 4 the dishes treated thereby, it is obvious that dishes may be otherwise delivered to the apron 4, as by the hand of an attendant, duly assorted as to size, contour or depth, and accordingly delivered into the various storage channels of the construction as a whole.

It will be seen that my improved dish receiver is particularly well adapted for the purposes for which it is intended, and further that the same may be modified to a considerable extent, particularly as regards the character of the selective means made use of, the specific form of the various fenders availed of, and various minor details of the general construction, without materially departing from the spirit and principle of my invention.

I claim:

1. A dish receiver comprising a channel for the reception and temporary storage of dishes; means for feeding dishes, one after the other, into said channel; and means for fending each dish at rest within said channel against direct impact from the next incoming dish.

2. A dish receiver comprising a plurality of channels for the reception and temporary storage of dishes; means for feeding various types of dishes for delivery, one after the

other, into said channels; and selective means for insuring the delivery of the respective types of dishes thus fed, into the channel or channels provided to receive the same.

- 5 3. A dish receiver comprising a channel for the reception and temporary storage of dishes; means for feeding dishes, one after the other, into said channel; and a series of pivotally disposed fenders, the latter arranged at intervals along said channel, and adapted to be automatically adjusted, each by a dish when approaching its position of rest within the channel, and so as to fend said dish against direct impact from the 10 dish next coming into and moving along said channel.

4. A dish receiver comprising a plurality of channels for the reception and temporary storage of dishes; means for feeding various 20 types of dishes for delivery, one after the other, into said channels; and selective means for insuring the delivery of the respective types of dishes thus fed, into the channel or channels provided to receive the same, each 25 of said channels having a series of fenders pivotally disposed at intervals therealong, and said fenders being adapted to be automatically adjusted, each by a dish when approaching its position of rest within said 30 channel, and so as to fend said dish against direct impact from the dish next coming into and moving along said channel.

5. A dish receiver comprising a primary receiving trough; means for feeding dishes 35 therein, one after the other; a channel for the reception and temporary storage of the dishes thus fed into said trough, the latter communicating with said channel; and means for fending each dish when at rest 40 within said channel, against direct impact from the dish next coming into said channel.

6. A dish receiver comprising a primary receiving trough; means for feeding dishes therein, one after the other; a channel for 45 the reception and temporary storage of the dishes thus fed; a box-like head intermediate of said channel and said trough, and establishing communication between them; and means for fending each dish, when at 50 rest within said channel, against direct impact from the dish next coming into said channel.

7. A dish receiver comprising a channel for the reception and temporary storage of 55 dishes; means for feeding dishes, one after the other, into said channel, the latter being provided with a series of pockets, each for the reception of one of said dishes; and a series of fenders, the latter movably disposed 60 one at each of said pockets, and adapted to be automatically adjusted, each by a dish when entering one of said pockets, and so as to fend such dish against direct impact from the dish next coming into said channel.

65 8. A dish receiver comprising a plurality

of channels for the reception and temporary storage of dishes; means for feeding various types of dishes for delivery, one after the other, into said channels, the latter being provided each with a series of pockets, each 70 for the reception of one of the dishes aforesaid; a series of fenders movably disposed, one at each of said pockets, and adapted to be automatically adjusted each by a dish entering any one of said pockets; and selective 75 means for insuring the delivery of the respective types of dishes thus fed, into the channel or channels provided to receive the same.

9. A dish receiver comprising a primary 80 receiving trough; a plurality of channels for the reception and temporary storage of dishes; a box-like head intermediate of said channels, respectively, and said trough, and communicating with the latter, said head 85 having a series of openings varying in dimensions and whereby communication is established between said box-like head and each of said channels, respectively; and means for feeding dishes into said trough 90 for ultimate delivery into said channels, by way of the said box-like head and the respective openings therein.

10. A dish receiver comprising a channel for the reception and temporary storage of 95 dishes; feed mechanism, for feeding dishes, one after the other, for delivery into said channel; a bridge between said feed mechanism and said channel; and means for fending each dish, when at rest within said channel, against direct impact from the next incoming dish. 100

11. A dish receiver comprising a channel for the reception and temporary storage of dishes; feed mechanism for feeding dishes 105 for delivery into said channel; and a displaceable bridge, the latter serving to establish communication between said feed mechanism and said channel.

12. A dish receiver comprising a channel 110 for the reception and temporary storage of dishes; a primary receiving trough; a box-like head, the latter establishing communication between said channel and said trough, said channel, box-like head and trough being 115 interiorly cushioned, respectively; and means for feeding dishes into said trough.

13. In a dish receiver, in combination, a channel for the reception and temporary storage of dishes; an endless apron for feeding dishes for delivery into said channel; and means for actuating said apron. 120

14. In a dish receiver, in combination, an endless apron for feeding dishes; means for actuating said apron; a channel leading 125 from said apron, and in communication with only a portion thereof; and means for deflecting dishes from the remaining portion of said apron toward, and for delivery into, said channel.

15. In a dish receiver, in combination, a primary receiving trough; feed mechanism for feeding dishes therein; a bridge, hinged to said trough; a channel for receiving dishes from said bridge; and channels for receiving dishes from said trough, said bridge, when spanning said trough serving to direct dishes coming from said feed mechanism into the channel first above named, and accordingly prevent their entrance into said trough, and when not spanning said trough, permitting the delivery by said feed mechanism of dishes therein.
16. In a dish-receiver, in combination,

endless mechanism for feeding dishes varying in depth; means for actuating said mechanism; and a rod, the latter disposed somewhat above, and obliquely to, said mechanism, and constituting a deflector whereby dishes of a substantial depth are guided obliquely and laterally along said mechanism, while dishes of a less depth are permitted to pass thereunder and move uninterruptedly with said mechanism.

ROBERT R. PARRY.
